United States Patent Office

Des. 217,338
Patented Apr. 28, 1970

217,338

FOOD TRAY OR THE LIKE

Thomas M. Britt, Red Bank, N.J., assignor to Owens-Illinois, Inc., Toledo, Ohio, a corporation of Ohio

Filed June 6, 1969, Ser. No. 17,560

Term of patent 14 years

Int. Cl. D9—04

U.S. Cl. D9—219

FIG. 1

FIG. 2

FIG. 3

FIG. 4

FIG. 5

FIG. 6

FIG. 1 is a top view of a food tray showing my new design;

FIG. 2 is a front elevational view;

FIG. 3 is a side elevational view;

FIG. 4 is a bottom plan view;

FIG. 5 is a cross-sectional view taken along the line 5—5 of FIG. 1; and

FIG. 6 is a cross-sectional view taken along the line 6—6 of FIG. 1.

I claim:

The ornamental design for a food tray or the like, substantially as shown.
